UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FACE-PLATE FOR FLUSH RECEPTACLES.

1,342,237.

Specification of Letters Patent.

Patented June 1, 1920.

Application filed December 4, 1915. Serial No. 65,130.

To all whom it may concern:

Be it known that I, GEORGE B. THOMAS, a citizen of the United States of America, and residing at Bridgeport, in the county of 5 Fairfield and State of Connecticut, have invented a certain new and Improved Face-Plate for Flush Receptacles, of which the following is a specification.

My invention relates to face plates for 10 flush receptacles and particularly to the mounting of the doors which close the entrance aperture through the face plate. The object of my invention is to provide an economical and secure means for holding 15 these doors.

In the accompanying drawing,

Figure 1 is a plan view of a face plate;

Fig. 2 is an inverted plan thereof in which 20 my invention is embodied in illustrative form;

Fig. 3 is a perspective of portion of the face plate viewed from the inner face thereof;

Fig. 4 is a perspective of one of the hinge 25 blocks;

Fig. 5 is a section through the plate showing a rivet in position preparatory to riveting operation;

Fig. 6 is a similar view showing the rivet 30 smashed down into place; and

Fig. 7 is a perspective of one of the rivets.

The invention is disclosed in the accompanying drawings as applied to a face plate 10 of the type having a rectangular opening 11 closed by two doors 12 and 13 pivoted on hinge rods 14 and 15 at opposite ends of the opening 11. These rods are secured in 35 grooves 16 and 17 in the inner face of the plate by means of hinge plates 18, 19, 20 and 21 each of which is grooved at 22 to receive the hinge pins. These plates are secured to the face plate by means of rivets 23, one to 40 each plate. In order that there may be no opportunity to swivel on these single rivets, 45 I form the latter of rectangular shape making the apertures to receive the same in the face plate and hinge plates of like rectangular shape. These apertures are also preferably countersunk or beveled at their oppo-

50 site ends at 24 to receive on the one hand the beveled head 25 of the rivet, and on the other hand to permit the inserted end of the latter to be spread lengthwise of the aperture 24 instead of expanding it in all di-

rections as is ordinarily the case in a rivet- 55

ing operation where a round rivet is used. A second set of hinge plates 26, 27, 28 and 29 is provided to secure the doors 12 and 13 to the hinge pin. The rivets 23 for this purpose, one for each hinge pin, are of the same 60 character as those just described. In addition each of these hinge plates is provided with a lug 30 extending beyond the margin of the door adjacent its free end and serving as a stop which impinges against the inner 65 face of the face plate 10 and halt the doors flush with the outer face of the face plate. The doors are normally held in their closed position by means of springs 31 and 32 coiled on the arms 33 and 34 integral with the 70 hinge plates 19 and 20, but offset therefrom and spaced from the inner face of the face plate so that the springs 31 and 32 may be freely passed over the ends of the arms and into adjusted position. To prevent possible 75 escape of the springs from these arms, the latter are provided with downturned ends 35 and 36 which form abutments against which the springs bear under any tendency of the latter to longitudinal displacement on said arms. These springs are in the form of coil 80 springs, one end 37 bearing against the face plate, and the other end 38 working in grooves 39 cut in the inner faces of the doors.

In the present face plate the doors 12 and 13 are provided with wearing ribs 40 on their outer faces. As a matter of economy 85 these are not formed in one with the doors but are made as independent pieces riveted 90 at 41 to the doors.

The present construction is extremely 95 economical since the rivets 23 may be struck from sheet metal of the same character as that from which the face plate itself is made, so that when the face plate has been planed and finished it is practically impossible to distinguish the metal of the rivets from that of the face plate. Furthermore, by reason of the fact that they are struck 100 from sheet metal and are of rectangular shape, a single rivet suffices to hold each hinge plate without danger of swiveling. The stop lugs 30, being formed integral 105 with certain of the hinge plates, afford economical stop means and are particularly desirable since they obviate the necessity of an operation upon the doors 12 and 13 out

of which the stop lugs have heretofore generally been formed. Similarly, the method of mounting the hinge springs is advantageous since it facilitates their assembly and 5 permits of their ready renewal in case of breakage.

Modifications of detail which do not depart from what I claim as my invention will readily occur to those skilled in the art and 10 I do not limit my invention to the precise structure shown.

I claim as my invention:—

1. An apertured sheet metal face plate for flush receptacles comprising a hinged sheet metal door for the aperture in the face plate, a hinge pin on which said door is pivoted, a hinge plate for holding said pin, and a single rectangular rivet for uniting said hinge plate to the under side of the face 20 plate, said plates being perforated in register by rectangular holes to receive said rivet.

2. An apertured sheet metal face plate for flush receptacles comprising a hinged sheet metal door for the aperture in the face plate, a hinge pin on which said door is pivoted, a hinge plate for holding said pin, and a single rectangular rivet for uniting said hinge plate to the under side of the face plate, said plates being perforated in 30 register by rectangular holes to receive said rivet, said holes being inwardly beveled on a single axis.

3. An apertured sheet metal face plate for flush receptacles comprising a hinged door for the aperture in the face plate, a hinge pin on which said door is pivoted, a hinge plate for holding said pin, and a single rectangular rivet for uniting said hinge plate to the under side of the face plate, 35 said plates being perforated in register by rectangular holes to receive said rivet, said holes being inwardly beveled on a single axis, and said rivet having at one end a head beveled to fit the hole in one of said 45 plates.

4. An apertured face plate having a hinged door for the aperture in the face plate, a hinge pin on which said door is pivoted, a hinge plate carried by the door 50 and engaging said hinge pin, said plate having a lug projecting beyond the margin of the door to form a stop adapted to engage the face plate and limit the extent of oscillation of the door.

5. An apertured face plate having a hinged door, a spring engaging the door to maintain the same normally closed, a hinge pin on which the door is pivoted, a hinge plate carried by the face plate and retaining 60 said hinge pin, and an offset arm on said hinge plate carrying the door spring.

6. An apertured face plate having a hinged door, a spring engaging the door to maintain the same normally closed, a hinge 65 pin on which the door is pivoted, a hinge

plate carried by the face plate and retaining said hinge pin, and an offset arm on said hinge plate carrying the door spring, said spring arm lying spaced from the face plate to permit the ready adjustment or removal of the spring, substantially as described. 70

7. An apertured face plate having a hinged door, a spring engaging the door to maintain the same normally closed, a hinge pin on which the door is pivoted, a hinge plate carried by the face plate and retaining said hinge pin, and an offset arm on said hinge plate carrying the door spring, said spring arm lying spaced from the face plate 80 to permit the ready adjustment or removal of the spring and having at its free end an offset approaching the face plate to prevent the accidental escape of the spring from said arm. 85

8. In an electrical device, an exposed sheet metal cover plate, an associated metallic member at the back thereof, said parts being pierced in register by rectangular apertures beveled on a single axis and inwardly toward the meeting faces of said members, in combination with a rectangular rivet of metal homogeneous with that of the cover plate, said rivet passing through said apertures and being spread at its opposite ends into engagement with the beveled walls of the aperture and being flush with the face of the cover plate in the finished device, the homogeneity of the metal of the rivet and cover plate serving to render the rivet indistinguishable from the cover plate and having the same appearance as the latter irrespective of the finish imparted to the surface. 90

9. In an electrical device, a sheet metal face plate apertured to afford an entrance opening, a sheet metal door arranged in said opening, a hinge pin on which said door is pivoted, a hinge plate engaging said pin, said plate and its associated member being pierced in register by rectangular apertures, in combination with a rectangular sheet metal rivet engaged in said registering piercings to hold said hinge plate and its associated member rigidly together. 105

10. In an electrical device, a sheet metal face plate, an independent element associated therewith, said face plate and associated element being pierced in register by rectangular apertures, together with a rectangular rivet of homogeneous sheet metal engaged in said apertures and serving to hold said parts together. 110

In testimony whereof I have signed my name to this specification in the presence of 125 two subscribing witnesses.
